SUCTION NOZZLE WITH REMOVABLE
BRUSH MEANS

Charles H. MacFarland, Rocky River, Ohio, assignor to
The Scott & Fetzer Company, Cleveland, Ohio, a corporation of Ohio

Application March 20, 1957, Serial No. 647,247

3 Claims. (Cl. 15—395)

This invention relates to vacuum cleaner nozzles and more particularly to so-called crevice tools and the like which are provided with a narrow elongated body intended for use in vacuum cleaning of relatively restricted spaces. More particularly the invention relates to suction nozzles which are provided with removable brush means.

Nozzles having releasable brush means have heretofore been provided in which the brush is rigidly connected to holders intended for insertion into the tool with screws or other securing means being provided to fasten the holder within the tool. Such an arrangement is inconvenient in that the brush cannot be readily snapped onto and removed from the tool.

Other structures have been provided in which the vacuum nozzle proper is received within a tubular member associated with the brush structure. A drawback of this structure is that the nozzle-receiving brush structure makes the tool, as a whole, rather bulky thus negativating the usual inherent advantages of the provision of a flat narrow nozzle or crevice tool.

These devices of the prior art have been improved upon by the provision of brush-mounting clip-on structure in combination with crevice tools provided with recesses to receive and anchor the clip-on structure. However, devices of this type have been relatively complex in that they require the assembly of a clip-on stirrup element to which is added a brush supporting element.

An object of the invention is to provide removable brush structure which is simpler and less expensive to manufacture than any similar devices of the prior art.

Another object of the present invention is to provide a suction nozzle having a removable brush means where the brush means comprises a single stirrup-shaped member which is arranged in a conformation to function both as the brush bristle mount and also the clip-on attaching means.

Another object of the invention is to provide a nozzle with removable brush structure which can be very readily and conveniently removed and inserted in the nozzle as desired and which is neatly and compactly arranged so as to interfere with the vacuum intake to a minimum extent.

According to the present invention the removable brush structure includes a single nozzle stirrup member which is so formed as to comprise a central bridging portion extending transversely between two arm portions, with the central bridging portion being joined to the arm portions by connecting portions which are bulged outwardly from the axial extent of the arm portions and then turn inwardly to the bridging portion.

A specific embodiment of the invention is described in detail below and is illustrated in the accompanying drawings. This embodiment is set forth merely by way of example. In the drawings:

Figure 1 is a side elevation of a suction nozzle pro-

2

vided with removable brush means in accordance with the invention.

Figure 2 is a partially broken away view on an enlarged scale taken from plane 2—2 in Figure 1.

Figure 3 is a side elevation, partially in cross-section, of the structure shown in Figure 2.

Figure 4 is a section taken on the plane of line 4—4 in Figure 3.

Figure 5 is a view of the stirrup and brush structure seen in the previous figures in its expanded or removed condition.

Figure 6 is a view similar to Figure 3 showing the vacuum nozzle structure with the stirrup and brush means removed therefrom.

Figure 7 is a fragmentary view of an alternative form of one detail of the invention.

In Figure 1 there is shown a vacuum nozzle consisting of metallic or resinous material. The nozzle 10 has a flattened tubular head 11 and a round tubular shank 12 which is adapted to receive or be connected to a vacuum cleaner hose or tube handle or hollow handle 13. The nozzle will be seen to comprise a flattened hollow body formed with spaced-apart side walls 14 and 15 and substantially smaller edge walls 16 and 17 and terminating in the end opening 18. The edge walls 16 and 17 of the nozzle have longitudinal grooves 20 formed therein adjacent the opening 18. The grooves 20 are of a smaller width than the width between the spaced-apart side walls 14 and 15, thereby defining shoulders 21 on either side of each of the grooves 20.

There is also provided a resilient stirrup member generally indicated by the reference numeral 25. This stirrup member comprises spaced apart arms 26 and 27 and a bridging portion 28 transverse to the arms 26 and 27. The arms are joined to the bridging portion by connecting portions 29 and 30. As shown in the drawings, the connecting portions bulge outwardly from the axial extents of the arms and then turn inwardly to the bridging portion 28. The stirrup member 25 may be formed as a twisted-wire core which secures brush elements or bristles 31, the provision of twisted-wire-supported brush elements being well known. Bristles 31 are positioned or supported on the bridging portion 28 and also on the connecting portions 29 and 30. The free or inner ends of the arms 26 and 27 may have positioned thereon projections such as the solder balls 33 and 34 which may be formed by dipping the ends of the arms 26 and 27 into a pool of molten solder.

When the stirrup member 25 is inserted into the nozzle 10, as indicated in Figure 3, the arms 26 and 27 are positioned over the associated grooves 20 and are sprung-urged away from each other by the resiliency of the stirrup member which tends to assume the conformation illustrated in Figure 5. The arms 26 and 27 fit within the grooves 20 to effect a keying interengagement with the grooves. Thus, the stirrup 25 is held against rotation relative to the nozzle. The solder balls 33 and 34 firmly but releasably hold the stirrup member in the nozzle by engaging the ends of the shoulders 21. The outer bulging connecting portions 29 and 30 engage the rim of the nozzle to limit inward movement of the arms into the nozzle. The stirrup structure is firmly and securely held in place as just described but it can be readily removed by pushing inwardly on the connecting portions 29 and 30 until the solder balls 33 and 34 clear the ends of the shoulders 21 and then pulling the stirrup structure outwardly from the nozzle. The stirrup structure can be re-inserted into the nozzle by manually urging the arms 26 and 27 together until the solder balls 33 and 34 can be placed against the shoulders 21 whereupon the stirrup member may be thrust into the tool until the outwardly

bulging solder balls 33 and 34 drop over the ends of the shoulders 21.

Projecting means other than the solder balls 33 and 34 may be provided. For example, the stirrup member may be provided at the ends of its arms with sleeves, such as the sleeve 35 shown in Figure 7. The sleeves 35 may have flanges 36 which coat with the ends of the shoulders 21 in much the same manner as do the solder balls 33 and 34. The sleeves 35 are fastened to the arms of the stirrup member by being crimped thereon.

In some instances it may be preferred to omit one of the projections at the ends of the arms 26 and 27 (the solder balls 33 and 34 or sleeves such as the sleeve 35), sufficient anchoring being obtained by the provision of projection means in association with only one of the arms.

The scope of the invention is not limited to all the details of embodiments of the invention described above but is to be defined by the following claims.

What is claimed is:

1. A suction nozzle having removable brush means, the nozzle having a flattened hollow body formed with spaced-apart side walls and substantially smaller edge walls and terminating in an end opening, the edge walls of the nozzle having longitudinal grooves formed therein adjacent the end opening of the nozzle, the grooves being of smaller width than the width between the spaced-apart side walls to define shoulders on either side of each of the grooves which shoulders terminate at a location spaced from the end opening of the nozzle, a resilient stirrup member comprising spaced-apart arms insertable through said end opening and a bridging portion transverse to the arms, the arms being joined to the bridging portion by connecting portions which bulge outwardly from the axial extent of the arms and then turn inwardly to the bridging portion, brush bristles supported on the bridging portion and the connecting portions, at least one of the arms having projecting means extending radially therefrom adjacent its free end, the arms being positioned over the grooves when the stirrup is positioned in the nozzle and being spring-urged away from each other and toward keying interengagement with said grooves along at least a portion of their length to key the stirrup member against rotation relative to the nozzle, said projecting means associated with said at least one of the arms being engaged with the termination of the shoulders defined at the sides of the groove associated with said at least one of the arms to firmly but releasably hold the stirrup member in the nozzle, the outwardly bulging connecting portions of the stirrup member engaging the rim of the nozzle to limit inward movement of the arms into the nozzle.

2. A suction nozzle having removable brush means,

the nozzle having a flattened hollow body formed with spaced-apart side walls and substantially smaller edge walls and terminating in an end opening, the edge walls of the nozzle having longitudinal grooves formed therein at least adjacent the opening of the nozzle, the grooves being of smaller width than the width between the spaced-apart side walls, a resilient stirrup member comprising spaced-apart arms insertable through said end opening and a bridging portion transverse to the arms, the arms being joined to the bridging portion by connecting portions which bulge outwardly from the axial extents of the arms and then turn inwardly to the bridging portion, brush bristles supported on the bridging portion and the connecting portions, the arms being positioned over the grooves when the stirrup is positioned in the nozzle and being spring-urged away from each other and toward keying interengagement with said grooves along at least a portion of their length to releasably hold the stirrup member in the nozzle and key it against twisting relative to the nozzle, the outwardly bulging connecting portions of the stirrup member engaging the rim of the nozzle to limit inward movement of the arms into the nozzle.

3. A suction nozzle having removable brush means, the nozzle having a flattened hollow body formed with spaced-apart side walls and substantially smaller edge walls and terminating in an end opening, the edge walls of the nozzle having longitudinal grooves formed therein at least adjacent the opening of the nozzle, the grooves being of smaller width than the width between the spaced-apart side walls, a resilient stirrup member comprising spaced-apart arms insertable through said end opening and a bridging portion transverse to the arms, the arms being joined to the bridging portion by connecting portions, brush bristles supported on the bridging portion and the connecting portions, the arms being positioned over the grooves when the stirrup is positioned in the nozzle and being spring-urged away from each other and toward keying interengagement with said grooves along at least a portion of their length to releasably hold the stirrup member in the nozzle and key it against twisting relative to the nozzle.
